US00D867814S

(12) **United States Design Patent** (10) **Patent No.:** **US D867,814 S**
(45) **Date of Patent:** **** Nov. 26, 2019**

(54) **LID**

(71) Applicant: **PI-Design AG**, Triengen (CH)

(72) Inventor: **Jorgen Bodum**, Meggen (CH)

(73) Assignee: **PI-Design AG**, Triengen (CH)

(**) Term: **15 Years**

(21) Appl. No.: **29/656,136**

(22) Filed: **Jul. 10, 2018**

(30) **Foreign Application Priority Data**

Jan. 31, 2018 (WO) DM/099637

(51) **LOC (12) Cl.** **07-99**

(52) **U.S. Cl.**

USPC **D7/392.1**

(58) **Field of Classification Search**

(57) **CLAIM**

The ornamental design for a lid, as shown and described.

DESCRIPTION

FIG. 1 is a perspective view of a lid showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the lid that form no part of the claimed design.

The “bodum” logo in the drawings, forming no part of the claim, is a registered trademark of PI-Design AG.

1 Claim, 7 Drawing Sheets
